VULCANIZING MECHANISM

Russell George Tilton, Mountain Lakes, N. J., assignor to Otis Elevator Company, New York, N. Y., a corporation of New Jersey

Application May 18, 1942, Serial No. 443,508

8 Claims. (Cl. 18—38)

The invention relates to vulcanizing mechanism for splices in moving stairway handrails.

Moving stairways are provided with two handrails, one on each side of the stairs and driven in synchronism with the steps. On both the upper run and the return run of the stairway incline, the handrails slide on guides extending inside the handrails. At one end of the stairway, the handrails pass around driving wheels and at the other end around idler wheels to make the return.

The handrail before it is installed on the stairway is a single length piece long enough to permit the ends to be spliced together to form a loop after it has been strung onto the stairway. It is the practice in splicing present day traction driven handrails to form complementary ends on the handrail which are cemented together in overlapping relationship with vulcanizable rubber utilized at certain points in the joint and to complete the joinder by vulcanization. Repair of existing handrails is effected in a similar manner, the rail being shortened and respliced or a new section is spliced into an old rail.

The object of the invention is to provide improved vulcanizing mechanism for the splicing of moving stairway handrails.

Features and advantages of the invention will become apparent from the following description and appended claims.

In the drawings:

Figure 1 is a view in perspective of moving stairway handrail vulcanizing mechanism embodying the invention, with a handrail in place;

Figure 2 is an end view of the same, also with the handrail in place;

Figure 3 is a fragmental end view of the same, similar to Figure 2, but without the handrail and with the top removed, illustrating the mechanism in condition to receive the handrail;

Figure 4 is a view in vertical section taken crosswise of the vulcanizing mechanism, with the handrail in place;

Figure 5 is a fragmental view in vertical section but taken lengthwise of the mechanism, also with the handrail in place;

Figures 6 and 7 are details of the complementary ends of the handrail prior to making the joint; and

Figure 8 is a detail of the handrail with the ends joined together ready for insertion in the vulcanizing mechanism.

Referring to the drawings, the invention will be described as adapted for a C-shaped traction drive handrail. Such handrail designated 10 is

of rubber with layers of reinforcing canvas, the inner layer of canvas forming the inner surface of the handrail thereby facilitating sliding of the handrail on its guides. The vulcanizer comprises a mould formed of two halves which will be termed the upper mould block and the lower mould block, these blocks being designated 11 and 12 respectively. These mould blocks are of the same shape and are iron castings. Each block is provided with a cover 13 between which and the block is a layer of heat insulating material 14. The cover is formed with flanges 15 at its ends and is secured to the block by screws 16.

The faces 17 of the mould blocks are machined to provide a good fit. Oppositely disposed depressions 20 and 21 are formed in the faces of the upper and lower blocks respectively to receive the handrail. Depression 21 has a raised portion 22, the sides 23 of which provide abutting surfaces for the tips 24 of the C formation of the handrail. On the raised portion are a pair of filler rods 26 and 27 shaped to conform to the inside of the handrail. The inner edges 30 of the filler rods are at an angle and flat to bear against the sides of an upwardly extending V-shaped stop 31 formed on the raised portion. Also the bottoms of the filler rods have flat surfaces 32 which bear against the flat surfaces 33 of the raised portion. Thus the depressions, the raised portion and the filler rods form a longitudinal passage of the same cross section as the handrail.

Each filler rod is provided at each end with a pivot pin 34 extending into longitudinally aligned apertures 35 in the rod and secured therein by set screws 36. At each end of the mould the pins for the two filler rods are rotatably supported in horizontally aligned apertures 37 provided in a vertically movable slide 40. Beyond the slide 40 each pin is provided with an operating handle 41. Each slide has a vertical slot 42. A shoulder screw 43 extends through the slot and is secured to the lower mould block in position to form a guide for the upper end of the slide. The slide 40 extends below the lower mould, the flanges 15 being cut away at 44 to permit the slide to bear against the end of the mould block. A pair of U-shaped brackets 45, one at each end of the lower mould block, are secured as by welding to brackets 45 and 46 in turn secured as by screws 48 to the bottom of the lower mould block. Each bracket is formed with an aperture 46 in the yoke thereof to receive a lock member 47. A nut 50 and lock washer 51 are provided on the threaded end of the lock member and tightened against

a shoulder 52 on the lock member, this nut and lock washer and an enlarged portion 53 formed on the lock member on the other side of the yoke acting to retain the lock member on the bracket while permitting rotative movement thereof. This enlarged portion is partially cylindrical being cut away to form parallel sides 54 so as to fit into the slot 42, thus providing a lower guide for the slide. The lower end of the slot is enlarged at 55 to permit rotative movement therein of the enlarged portion 53 of the lock member when the slide is in its uppermost position. Beyond the slide the lock member is provided with a handle 56 for rotating the lock member when the slide has been moved into its uppermost position to lock the slide in that position. An aperture 57 is provided in the lower end of the yoke of each bracket 45 to receive a removable pin 58 which extends through the slot 42 in the slide at the bottom thereof when the slide is in its lowermost position to lock the slide against upward movement. To prevent loss, this pin is connected by a chain 59 to the handle 56.

The mould blocks are clamped together by means of bolts 60. Six of these bolts are utilized, these bolts being arranged in crosswise aligned pairs, one pair at each end of the mould and one pair in the middle. Each bolt has a separate head 61 screwed onto the upper end of the bolt and held by a set screw 62. Each bolt is provided with a T handle 63 slideable in an aperture 64 in the bolt head. Pins 65 are provided in the ends of the handle to prevent the handle coming out of the aperture 64. Aligned apertures 66 are provided in the mould blocks to receive these bolts. Each bolt is threaded on its lower end 67 and each aperture in the lower block is threaded at 70 to receive the threaded end of the bolt. The shank 71 of each bolt above the lower end is of reduced diameter to permit the bolt to slide in the upper mould block. A bushing 72 is provided on top of the upper mould block immediately above each aperture therein to form a guide for the shank of the bolt and to prevent the bolt being removed from the upper mould block. These bushings are held in place in apertures provided in the cover 13. The top portion 73 of each aperture in the upper block is threaded to receive the threaded end of the bolt to facilitate lifting the upper block from the lower block. The remainder of each aperture in the upper block is reamed out to permit the threaded end 67 of the bolt to slide in the upper block when it is unscrewed from the lower block. The lower tip 74 of each screw is of reduced diameter and provided with a tapered end 75 and the upper part 76 of each aperture in the lower block is reamed out. This construction facilitates starting the bolt in the threaded portion 70 of the aperture.

Each mould block is formed with an additional depression 80, the depression in the upper block being in the top of the block and the depression in the lower block being in the bottom of the block. These depressions are for the heater elements 81. These elements are standard strip type heater elements and are secured to the blocks in the bottoms of the depressions as by screws 82. A C-shaped heat collector 83 is provided in each depression for the heater elements. Also arranged in each depression is a resistance 84. Each depression is filled with asbestos to serve as a heat insulator and to hold the resistance in position. The heater elements are provided with connecting screws 85 and the elements

and the resistances are connected by suitable conductors extending through insulating bushings 86 in the mould block to terminal boxes 93 and 95 on the upper and lower mould blocks respectively. Connection is made in terminal box 93 to a flexible conductor 100 having a plug 101. The top of the terminal box 95 is provided with two plug receptacles 105 and 106 for receiving the plug 101. A dummy plug 110 is also provided for inserting in receptacle 106, this plug being connected by a chain 111 to an eye bolt 112 secured to the terminal box. This chain is of a length to prevent the dummy plug being inserted in left hand receptacle 105. An additional plug receptacle 113 is provided in the bottom of the terminal box for receiving a connecting plug from a source of current supply. For 110 volt operation dummy plug 110 is inserted in right hand receptacle 106 and plug 101 is inserted in left hand receptacle 105, and for 220 volt operation plug 101 is inserted in right hand receptacle 106 and the dummy plug allowed to hang free.

Jewels are provided for indicating whether or not the moulds are heating, the left hand jewel 115 being for the upper mould block and the right hand jewel 116 for the lower mould block as indicated by the arrows in the jewels. The jewels are illuminated by lamps 120 connected across resistances 84.

30 A thermometer 125 is provided for recording the temperature of the vulcanizer. This thermometer is provided with protective casing 126 having a window 127 for making the reading. A safety chain 130 connected to the top 131 of the thermometer is detachably connected to an eye bolt 132 secured to the cover 96 of the terminal box. An aperture 133 extends through the upper mould block partially into the lower block to receive the thermometer, a guide bushing 134 aligned with the aperture being provided in the cover 13.

For use, the vulcanizing unit is clamped to the upper handrail guide 140. This guide is secured by bolts 141 to the balustrade 142 of the stairway.

45 The guide is illustrated as comprising an upper guide flange 143 and a lower guide flange 144. The brackets 145 and 146, which as previously described are secured to the lower mould block, are angle brackets extending longitudinally of the mould block. The left hand bracket 145 as viewed in Figure 4 is bent inwardly along its lower edge to form a jaw 147 to fit into the space between the upper and lower flanges 143 and 144 on the left hand side of the handrail guide. A pair of longitudinally spaced pins 150 are secured to the right hand bracket 146 immediately below the upper flange thereof to form a guide for a movable clamp 151. This clamp is of a U cross section with its lower leg 152 at an angle and forming a jaw to fit into the space between the upper and lower flanges 143 and 144 on the right hand side of the handrail guide. A pair of longitudinally spaced cylindrical blocks 153 are provided between the vertical legs of brackets 145 and 146. These blocks are of reduced diameter

60 at their ends to fit into apertures 154 provided in the sides of the brackets. The outer ends of the blocks are threaded and are provided with nuts 155 and lock washers 156 to clamp the blocks to the brackets. Each block is provided with an aperture 157, the left hand portion 160 of which is threaded to receive the threaded end of a clamping bolt 161. The remainder of aperture 157 is reamed out to permit movement there- 70 in of the shank 162 of the bolt. The yoke 163 of

clamp 151 is provided with a pair of apertures 164 aligned with apertures 151 for receiving the shanks of the bolts. The heads 165 of the bolts provide shoulders 166 to force the clamp 151 inwardly upon taking up on the bolts. Each bolt is provided with a T handle 167 slidable in an aperture in the head 165. Pins 170 are provided in the ends of the handle to prevent the handle coming out of the head. A compression spring 172 is arranged on shank 162 of each bolt between the clamp 151 and the block 153 for biasing the clamp outwardly. Each bolt is provided with a stop 171 on the left hand end thereof to limit its outward movement.

In installing a traction driven handrail, with the handrail tensioning mechanism fully released, the handrail is strung onto the guide for the return run and around the wheels and the ends are brought together off the guide at a point along the incline of the upper run. The ends are drawn together by a rope tackle. About twelve inches of extra rail length is allowed for making the joint. The ends of the rail are then held in wood stripping blocks and stripped back in sections one layer at a time. The stripping is done to form complementary male and female ends 175 and 176 on the handrail. The first stripping operation to provide the male end shown in Figure 6 is to remove the outer layer of capping rubber 177 down to the top layer of canvas 180. For a handrail construction of six canvas layers the cut is started about $7\frac{1}{2}$ inches back from the end of the handrail and is preferably made at a 45° angle as this gives a longer flexing line. The next stripping operation is to remove the first layer of canvas back about $\frac{1}{4}$ inch from the rubber capping previously removed and along a 45° line parallel to this cut to provide a set back portion 181. Each succeeding stripping operation is made by removing the remainder of the handrail down to the next layer of canvas from a point about $1\frac{1}{2}$ inches measured along the edge of the handrail closer to the end of the handrail and along cuts crosswise of the rail. The forming of the female end shown in Figure 7 is the reverse of that of forming the male end. The end is first cut off at a 45° angle extending in the same direction as that for the male end when the two ends are superimposed, and the rubber capping is cut back about $\frac{1}{4}$ inch at a 45° angle parallel to the end of the rail to expose the top layer of canvas, forming a set back portion 182. The inner layer of canvas is then removed from along a crosswise cut about $7\frac{1}{2}$ inches from the end of the rail measured along the short edge. The succeeding layers are then removed in a manner similar to that described for the male member. The ends of the handrail are then thoroughly cleaned with pure gasoline and two coats of rubber cement applied on exposed parts of both male and female ends except for the top set back portions 181 and 182. The first coat of cement is allowed to dry thoroughly before applying the second. After the cement has dried, the end step 183 of the male piece is covered with a thin layer of vulcanizable rubber such as tie gum and a strip of this material about $\frac{1}{2}$ inch wide is run along the bead 184 on each side. The two ends are then matched together with a piece of muslin in between them to prevent their sticking until properly matched. The muslin is then pulled out a little at a time and the cement coated surfaces pressed together. A piece of tie gum 185 is then fitted into the space provided by set back portions 181 and 182 in the

top of the rail between the capping layers, this strip being cemented in place by first applying two layers of rubber cement to the portions 181 and 182 in the manner previously described. The handrail joint thereby becomes as shown in Figure 8 and is ready for vulcanizing.

The lower mould unit is then clamped to the handrail guide on the incline of the upper run at the joint in the handrail but with the handrail out of the mould. To apply the clamp to the handrail guide, bolts 161 are turned outwardly, springs 172 holding movable clamp 151 against shoulders 166 on the bolts as the bolts are unscrewed, thereby increasing the space between the jaw members. When sufficient space exists between the ends of the jaw members, the clamp is lowered over the flanges 143 and the bolts are tightened to move the jaws into the space between flanges 143 and 144 until the clearance is taken up, thereby clamping the mould section to the handrail guide.

The interior surface of both sections of the mould are thoroughly cleaned and polished before using. The upper section of the mould is then put temporarily in place and with the proper connections made for the voltage of the particular power supply the mould is connected to the source of power long enough to bring the upper unit up to a temperature uncomfortable for the hands. The upper unit is then removed and soap applied to the surface which will leave a flaky residue. Pins 58 are then removed and the slides 40 at each end are lifted simultaneously to their uppermost position. Each slide is locked in this position by turning downwardly on handle 56 of locking member 47 to place the enlarged portion 53 crosswise in the end 55 of slot 42. Filler rods 26 and 27 are then rotated upwardly one at a time into the positions illustrated in Figure 3, this rotation being effected by means of the handles 41 at the ends of the rods. A small amount of soapstone powder is applied to the interior of the lower mould section and any excess wiped off the filler rod seats on the raised portion 22.

The handrail is now placed onto the filler rods with the splice longitudinally central with respect to the mould. The filler rods are then turned back to their horizontal positions one at a time by means of their handles 41. This places the filler rods inside the handrail. The handles 56 of locking members 47 are then turned back to horizontal position preferably by using chains 59 to obviate any injury to the hands. This places the enlarged portions 53 parallel with slots 42, permitting the slides 40 to be returned to their lowermost positions. The splice may be tapped with a mallet to insure full downward travel of the slides and that the splice fits properly in the mould. The upper mould section is then put in place. The upper mould section may be conveniently handled by screwing the end bolts 60 a short distance into the threaded portions 73 of the apertures in the upper mould block to retain these bolts in raised positions and by placing the handles of these bolts crosswise of the mould to use as grips. The center bolts are allowed to hang to act as guides in placing the upper mould block on the lower block. With the upper block in place, the bolts 60 are screwed into the lower section and taken up evenly by hand until the splice is snugly compressed. With the proper connections made for the voltage of the particular power supply the mould is connected to this source of power. Also thermometer 125 is placed

in the aperture 133 and its chain 130 connected to eye bolt 132.

As the temperature of the mould increases the bolts 60 are taken up evenly by hand at various times. When the temperature recorded by the thermometer reaches a certain point which for the particular compound of rubber usually used in handrails is 120° centigrade, the mould is disconnected from the source of power supply and the time at which this cut-off is made is recorded. The thermometer may now be removed from the mould. Thereafter any slack in the splice is occasionally taken up by tightening down evenly on the bolts 60 by hand. After power has been cut off for a certain period of time, thirty-five minutes for the particular rubber composition usually employed, bolts 60 are loosened and the upper section of the mould removed. Inasmuch as the handrail may tend to stick to the upper mould section, pins 58 should be in place at this time to prevent slides 40 and therefore the handrail being pulled upwardly. When the upper mould section has been removed pins 58 are removed and the slides 40 are moved upwardly and locked in place. The filler rods are then turned to their uppermost positions illustrated in Figure 3 to permit the handrail to be removed from the mould. Any side fins which may have formed on the handrail during the vulcanizing operation are removed and after the joint has cooled the junction is polished. The lower mould section is removed from the handrail guide and the handrail is sprung onto the handrail guide along the upper run. The handrail tensioning mechanism is taken up to condition the handrail for operation.

While the splicing of a new handrail installation has been described, it is to be understood that the vulcanizing mechanism may also be used to vulcanize splices in old handrails in case of repairs, including the splicing in of new handrail sections in old handrails. Also, the vulcanizing mechanism may be adapted to suit other types of handrails and to vulcanize joints in which the splices are made in other ways. The vulcanizing mechanism described has the advantage of being a compact unit of only two sections. The filler rods and their operating mechanism are integral with the lower mould section as is the clamp for the handrail guide. The bolts 60 are retained with the upper mould section as are the bolts 161 with the lower mould section. Thus the disadvantage and inconvenience of parts being lost or misplaced are obviated. It is to be understood however that various changes may be made in the construction of the vulcanizing mechanism and many different embodiments thereof could be made without departing from the spirit and scope of the invention. Therefore it is intended that all matter contained in the above description or shown in the accompanying drawings shall be interpreted as illustrative and not in a limiting sense.

What is claimed is:

1. Mechanism for vulcanizing a splice in a moving stairway handrail comprising; a mould formed of a pair of separable mould blocks arranged face to face, said blocks having longitudinal depressions formed in their faces opposite each other to provide an opening for the handrail; a pair of filler rods for the inside of the handrail extending longitudinally of the mould in said opening; an abutment for said rods; and means mounting said filler rods on one of said mould blocks and operable when said blocks are

separated to move said rods away from said abutment and to rotate said rods into position to receive the handrail splice.

2. Mechanism for vulcanizing a splice in a moving stairway handrail comprising; a mould formed of a pair of separable mould blocks arranged face to face, said blocks having longitudinal depressions formed in their faces opposite each other to provide an opening for the handrail; a pair of slides, one at each end of one of said mould blocks, movable perpendicularly to the face thereof; a pair of filler rods for engaging the inside of the handrail, said rods extending longitudinally of the mould in said opening and pivotally mounted at their ends on said slides; an abutment between said rods; and means for securing the blocks together.

3. Mechanism for vulcanizing a splice in a moving stairway handrail comprising; a mould formed of a pair of separable mould blocks arranged face to face, said blocks having longitudinal depressions formed in their faces opposite each other to provide an opening for the handrail; a pair of filler rods for engaging the inside of the handrail, said rods extending longitudinally of the mould in said opening; an abutment between said rods; means at each end of one of said mould blocks for pivotally supporting said filler rods, said supporting means being operable to move said rods away from said abutment when said mould blocks are separated so that said rods may be turned into position to receive the handrail splice and with the handrail splice in place thereon turned back to fit into the inside of the handrail, said supporting means being operable then to return said filler rods to engage the abutment, placing said handrail splice in the depression in said one mould block; and means for clamping the splice between said blocks.

4. Mechanism for vulcanizing a splice in a moving stairway handrail comprising; a mould formed of a pair of separable mould blocks arranged face to face, each of said blocks having a longitudinal depression formed in its face opposite the other to provide an opening for the handrail; a pair of filler rods for engaging the inside of the handrail, said rods extending longitudinally of the mould in said opening, one of said mould blocks being formed with an abutment in said depression therein for said rods; slidable means at each end of said one mould block for pivotally supporting said filler rods, said slidable means when said mould blocks are separated being movable in a direction to move said rods away from said abutment; means operable when said rods have been moved away from said abutment to turn the rods into position to receive the handrail splice and with the handrail splice in place thereon back to fit into the inside of the handrail, said slidable means being adapted to be then moved back to place said handrail splice in the depression in said one mould block; and means for securing the blocks to each other when they have been placed back together.

5. Mechanism for vulcanizing a splice in a moving stairway handrail comprising; a mould formed of a pair of separable mould blocks arranged face to face, said blocks having matching longitudinal depressions formed in their faces; a pair of filler rods extending longitudinally of the mould in the opening formed by said depressions, one of said mould blocks being formed with an abutment in said depression therein for said rods, said opening, filler rods

and portions of said abutment forming a longitudinal passage in the mould of the same cross section as the handrail; slideable means at each end of said one mould block for pivotally supporting said filler rods, said slideable means when said mould blocks are separated being movable in a direction perpendicular to the face of said one mould block to move said rods away from said abutment; means operable when said rods have been moved away from said abutment to turn the rods into position to receive the handrail splice and with the handrail splice in place thereon back to fit into the inside of the handrail, said slideable means being adapted to be then moved back to place said handrail splice in the depression in said one mould block; and means retained with the other of said mould blocks for securing the blocks to each other after they have been placed back together.

6. Mechanism for vulcanizing a splice in a moving stairway handrail comprising; a mould formed of a lower mould block and a removable upper mould block arranged face to face and separable, said blocks having matching longitudinal depressions formed in their faces; a pair of filler rods extending longitudinally of the mould in the opening formed by said depressions, the lower mould block being formed with an abutment in said depression therein for said rods, said opening, filler rods and portions of said abutment forming a longitudinal passage in the mould of the same cross section as the handrail; a pair of slides, one at each end of the lower mould block; means for pivotally supporting said filler rods in the upper ends of said slides, said slides when the upper mould block is removed being movable upwardly to lift said rods away from said abutment; means for locking said slides in their uppermost positions; means for manually turning said rods when the slides are in their uppermost position into upright position to receive the handrail splice and with the handrail splice in place thereon back to fit into the inside of the handrail, said slides being adapted to be then released and lowered to lower said handrail splice into the depression in the lower mould block; bolts for securing the upper mould block to the lower mould block after it is replaced thereon, aligned vertical apertures being provided in said blocks for said bolts; and means at the upper ends of the apertures in the upper mould block for retaining the bolts with the block.

7. Mechanism for vulcanizing a splice in a moving stairway handrail comprising; a mould formed of a lower mould block and a removable upper mould block arranged face to face, each having a heat insulating cover secured to the block and said blocks having matching longitudinal depressions formed in their faces; a pair of filler rods extending longitudinally of the mould in the opening formed by said depressions, the lower mould block being formed with an abutment in said depression therein for said rods, said opening, filler rods and portions of said abutment forming a longitudinal passage in the mould of the same cross section as the handrail; a plurality of pivot pins, one for each end of each filler rod and secured thereto; a pair of slides, one at each end of the lower mould block, each slide having a pair of horizontally aligned apertures in the upper end thereof to receive said pivot pins to pivotally support said filler rods in

parallel relationship, said slides when the upper mould block is removed being movable upwardly to lift said rods away from said abutment; means for locking said slides in their uppermost positions; means for manually turning said rods when the slides are in their uppermost position, said rods being turned upwardly to receive the handrail splice and with the handrail splice in place thereon being turned back to fit into the inside of the handrail, said slides being adapted to be then released and lowered to lower said handrail splice into the depression in the lower mould block; bolts for securing the upper mould block to the lower mould block after it is replaced thereon, aligned vertical apertures being provided in said blocks for said bolts, the lower end of each bolt being threaded, a portion of each aperture in the lower mould block being threaded to receive the threaded end of the bolt, said bolt being slideable in the apertures in the upper mould block; means at the upper ends of the apertures in the upper mould block for retaining the bolts with the block; and an electrical heating unit in each mould block.

8. Mechanism for vulcanizing a splice in a moving stairway handrail comprising; a mould formed of a lower mould block and a removable upper mould block arranged face to face, each having a heat insulating cover secured to the block and said blocks having matching longitudinal depressions formed in their faces; a pair of filler rods extending longitudinally of the mould in the opening formed by said depressions, the lower mould block being formed with an abutment in said depression therein for said rods, said opening, filler rods and portions of said abutment forming a longitudinal passage in the mould of the same cross section as the handrail; a pair of vertically movable slides, one at each end of the lower mould block, each slide having a pair of horizontally aligned apertures in the upper end thereof; a pair of pivot pins for each filler rod, one at each end thereof, said pins being secured to the ends of the filler rods and extending through said apertures in said slides to form pivotal supports for said rods; means for locking said slides in their uppermost positions; handles secured to the outer ends of said pins for manually turning said rods when the slides are in their uppermost position, said rods being turned upwardly to receive the handrail splice and with the handrail splice in place thereon being turned back to fit into the inside of the handrail; means for locking said slides in their lowermost positions; bolts for securing the upper mould block to the lower mould block, aligned vertical apertures being provided in said blocks for said bolts, the lower end of each bolt being threaded, a portion of each aperture in the lower mould block being threaded to receive the threaded end of the bolt and the upper end of each aperture in the upper mould block being threaded to retain the bolt with the block, the remainder of the aperture in the upper mould block being of enlarged diameter and the shank of each bolt being of reduced diameter to permit the bolt to slide in the aperture with respect to the upper mould block, each bolt having a cross-bar horizontally slideable in the bolt head to form a handle; and an electrical heating unit in each mould block.

RUSSELL GEORGE TILTON.
